UNITED STATES PATENT OFFICE.

HOWARD L. PARK, OF READING, MASSACHUSETTS.

FORM FOR MAKING CEMENT OR CONCRETE STEPS.

1,182,307.

Specification of Letters Patent.

Patented May 9, 1916.

Application filed February 3, 1915. Serial No. 5,932.

To all whom it may concern:

Be it known that I, HOWARD L. PARK, a citizen of the United States, residing at Reading, in the county of Middlesex and 5 State of Massachusetts, have invented certain new and useful Improvements in Forms for Making Cement or Concrete Steps, of which the following is a specification.

This invention relates to forms or molds 10 for making concrete or cement steps, and its object is to provide a simple and cheap device of this kind which can be easily and quickly set up ready for use, and which is adjustable to the height of the risers and the width of 15 the tread which the steps are to have.

This object is attained by means of a novel combination and arrangement of parts to be hereinafter described and claimed, reference being had to the accompanying drawings in 20 which—

Figure 1 is an end view of the form; Fig. 2 is a plan view thereof; Fig. 3 is a section on the line 3—3 of Fig. 2; Fig. 4 is a section on the line 4—4 of Fig. 3; Fig. 5 is a sectional detail showing a modification; Fig. 6 is an end view showing a coping form; Fig. 7 is a plan view of one end of the coping form; Fig. 8 is a section on the line 8—8 of Fig. 6, and Fig. 9 is a face view of one of the 30 coping plates.

In carrying out the invention there is provided a pair of laterally spaced, parallel side bars 10 carrying supporting members 11 of transverse, vertically-arranged boards 12, 35 which latter determine the risers of the steps. The bars 10 are spaced according to the width of the steps and the members 11 are adjustable relative to each other according to the width of the tread, and by employing 40 riser boards 12 of different heights, the height of the risers of the steps may be varied.

The side bars 10 are channeled in cross-section, with their flanges pointing outward, 45 and the members 11 are clamped to the inner faces of said bars by bolts 13 having hook-shaped ends 14 to engage over the flanges of the bars. The bolts carry wing nuts 15, and upon tightening up the latter, the members 11 are securely fastened to the side bars. The top bolts 13 pass through arcuate slots 50 16 in the members to allow the angle of the stairs to be changed, the side bars being mounted in an inclined position corresponding to the angle of the stairs. The side bars

are positioned vertically so that their flanges are at the top and the bottom. Upon loosening the nuts 15, the members 11 may be slid along the side bars to position the riser boards 12 according to the width of the 60 tread.

Each member 11 projects above and below the side bar 10 to which it is made fast, the lower projecting portion being reduced in width and having its rear edge straight, the 65 riser board 12 seating against said edge, below the side bar, and said edge having a brad 17 which is driven into the board to hold the same in place. The board is further secured by a pivoted, driven fastener 18 carried by 70 the member 11 and located so that it may be driven into the top edge of the board. The top edge of the member 11 supports a staging plank 19 on which the workman stands. At the front end of the member is an upstanding 75 lug 20 to prevent the plank from slipping off. Each member 11 also has a rearwardly projecting part 21 on the vertical edge of which is a scale 22 on which indicates a lapping horizontal pointer or finger 23 projecting 80 from the front edge of the adjacent member 11. The bottom edge of the pointer also has a scale 24 on which the edge of the adjacent member having the scale 22 indicates. These scales and co-operating parts obviate the ne- 85 cessity of measuring each riser, and enable the members 11 to be accurately positioned on the side bars 10 after setting the first member.

In operation, the side bars 10 are set up 90 at the required inclination, and spaced according to the width the steps are to have. The members 11 are adjusted on the side bars according to the width of the tread, and the riser boards 12 are mounted in place 95 and made fast as hereinbefore described, boards corresponding to the height of the risers being employed. The concrete mate- 100 rial is now filled in behind the lowermost riser board 12, and leveled off flush with the top of said board to form the tread of the first step. More material is now filled in behind the next riser board and the same is leveled off flush with said board, to form the 105 second step. This operation is repeated until the top riser board is reached and the steps are finished.

Instead of the channel bars 10, plain wooden stringers 25, as shown in Fig. 5 may be employed for supporting the members 11, 110

the latter being fastened on by bolts 26 passing across the top and bottom edges of the stringers and through slots 27 in a plate 28 mounted against the outer faces of the stringers.

The channeled bars 10 are designed to be used on long flights of steps, whereas the wooden stringers 25 may be employed on short flights.

At 29 are shown members for molding the inner face of a coping, said members being flat metal plates. To these plates are riveted or otherwise fastened angular bracket arms 30 having slots 31 to receive bolts 32 whereby the plates are mounted on the side bars 10, so that they extend in a row along the outer faces thereof, the length of the riser boards 12 being such that they fit between the plates on the respective sides of the device. The slots 31 have the same function as the slots 16 hereinbefore described. When the coping form is used the hook-shaped bolts 13 are not employed, but the bolts 32 are substituted for the same, the arms 30 fitting against the edges of the flanges of the side bars, and thus serving to coöperate with the bolts to secure the members 11 in the same manner as the plates 28 hereinbefore described.

The steps may be made with or without coping. If a coping is not desired, the plates 29 will, of course be left off.

The device provides a simple and cheap form for the purpose described, it is readily adjustable, and easily and quickly set up, it can be used over and over again, and it does not require skilled labor.

When the apparatus is in use a plain board form supports the concrete beneath the same, with side boards to keep the concrete from flowing out at the sides. On inside work this board frame may be in the form of a simple trough, and on outside work the earth, dirt or ground, when convenient, with boards on the sides, can be used to support the concrete and keep it from flowing out at the sides. When the concrete has set, the boards supporting the same are knocked out. The side bars 10 are above the treads of the step and on the inside of the coping, and a plank forms the outside of the latter. The side bars do not touch the concrete, and the latter is filled in up to the coping plates only. The coping plates are made high enough to keep their upper edges above the concrete, and thus prevent them from being embedded in the latter. In making a coping on steps the wooden trough hereinbefore referred to is

made a little wider so as to allow for the 60 width of the coping on each side.

I claim:—

1. A form for molding steps, comprising laterally spaced side bars, riser-forming members extending transversely beneath 65 said side bars, supporting members for the riser-forming members mounted on the side bars and adjustable along the same, said supporting members having portions depending from the side bars against the rear 70 of which the riser-forming members abut, means for securing the riser-forming members to said depending portions of the supporting members, the supporting members having vertical edge portions provided with 75 a scale, and a pointer, the pointer of a member indicating on the scale of an adjacent member.

2. A form for molding steps, comprising laterally spaced side bars, riser-forming 80 members extending transversely beneath said side bars, supporting members for the riser-forming members mounted on the side bars and adjustable along the same, said supporting members having portions depending 85 from the side bars against the rear of which the riser-forming members abut, means for securing the riser-forming members to said depending portions of the supporting members, the supporting members having 90 vertical edge portions provided with a scale, and a pointer, the pointer of a member indicating on the scale of an adjacent member, 95 said pointers having horizontal edge portions provided with a scale, the aforesaid vertical edge portion of a member indicating on the last mentioned scale of an adjacent member.

3. A form for molding steps, comprising laterally spaced side bars, riser-forming 100 members extending transversely beneath said side bars, supporting members for the riser-forming members mounted on the side bars and adjustable along the same, said supporting members having portions depending 105 from the side bars against the rear of which the riser-forming members abut, and means for securing the riser-forming members to said depending portions of the supporting members, said supporting members at the top projecting above the top of 110 the side bars and having a staging seat.

In testimony whereof I affix my signature in presence of two witnesses.

HOWARD L. PARK.
